GOLF CLUB CARRIER

Henry P. Yokers, Menomonee Falls, Wis., assignor to Sit 'N Rest Golf, Inc., Milwaukee, Wis.

Filed Apr. 23, 1968, Ser. No. 11,581

Term of patent 14 years

Int. Cl. D21—03

U.S. Cl. D34—5

FIG. 1 is a side elevation view of a golf club carrier showing my new design;

FIG. 2 is a front elevation view;

FIG. 3 is a rear elevation view, and

FIG. 4 is a top plan view.

The broken line showing of a golf club is for illustrative purposes only.

I claim:

The ornamental design for a golf club carrier, substantially as shown and described.
